UNITED STATES PATENT OFFICE.

EGBERT H. GOLD, OF CHICAGO, ILLINOIS.

ENGINE.

No. 848,985.

Specification of Letters Patent.

Patented April 2, 1907.

Application filed February 10, 1905. Serial No. 245,092.

To all whom it may concern:

Be it known that I, EGBERT H. GOLD, a citizen of the United States, residing at Chicago, in the county of Cook and State of Illinois, have invented certain new and useful Improvements in Engines, of which the following is a specification.

My invention relates to improvements in engines suitable for various uses, although shown for convenience as arranged in connection with a fluid-circulating system.

An object of my invention is to provide a rotary engine which may be operated with a minimum expenditure of steam or of like motor fluid, which may be operated by a steam-current which is used to supply a heating system in which there may be but a slight difference in pressure between the feed and exhaust sides of the engine, and to afford a mechanism in which the engine may be readily driven by a slight motor force and in such a manner that the engine will carry no load in its initial operation and will automatically unload whenever its speed becomes less than that required to carry the load. These and other objects are attained by my invention, which is more specifically set forth in the accompanying claims and which is shown in one convenient embodiment thereof in the accompanying drawings, in which—

Figure 1 is a sectional view through the engine mechanism and accompanying parts arranged for a circulating system. Fig. 2 is a sectional view on the line 2 2 of Fig. 1 looking in the direction indicated by the arrows. Fig. 3 is a like view on the line 3 3 of Fig. 1. Fig. 4 is a like view on the line 4 4 of Fig. 1. Fig. 5 is a like view on the line 5 5 of Fig. 1. Fig. 6 is a like view on the line 6 6 of Fig. 1. Fig. 7 is an enlarged sectional detail of a part of the engine mechanism. Fig. 8 is a sectional view on the line 8 8 of Fig. 7 looking in the direction indicated by the arrows, and Fig. 9 is a detail of one end of one of the motor-arms.

Like numerals of reference indicate the same parts in the several figures of the drawings.

As shown in the accompanying drawings, 1 indicates a supply-pipe for a suitable motor fluid, such as steam under pressure, through which steam flows into a chamber in the box 2, which is provided on one side of the motor-casing 3. Extending axially through the box 2 is the shaft 4, journaled

within the walls of the box 2 and extending outwardly through a stuffing-box 5. This shaft 4 also extends into and across the motor-casing 3 and is shown as journaled at 6 in 60 said casing. The shaft 4 has preferably some longitudinal play and is provided with a collar or flange 7. The inner end of the box 2 is closed by a cap 8, through which the shaft 4 extends and within which it may be 65 journaled, if desired. Loosely mounted on the shaft 4 and between the flange 7 and cap 8 is a packing-ring 9 of Jenkins material or any other kind of suitable material. The shaft 4 is hollow on the interior of the box 2 70 to the end which is journaled at 6, and it is provided with a perforation or passage 10, connecting the interior of the shaft with the interior of the box 2.

Mounted upon the shaft 4 within the motor-casing 3 are two sets of motor-arms 11 and 12, which are hollow, connecting the interior of the shaft 4 and which are provided with constricted openings at their outer ends, through which they discharge into the interior of the casing 3. The shaft 4 is preferably provided with an enlarged chamber 13, with which the motor-arms 11 and 12 are connected. Mounted upon the shaft 4 is a fly-wheel 15. The motor-arms 11 are bent 85 to discharge toward the angle formed by the wall 16 with the wall 17 of the casing 3, in or across which angle are arranged a plurality of corrugations or pockets 18, the wider faces of which extend in such a plane that the jets 90 discharged from the bent ends of the motor-arms 11 will strike vertically against said faces and so as to force the shaft 4 toward the bearing 6, as well as to rotate the shaft 4. The discharge ends of the motor-arms 12 are 95 also bent, but are preferably bent in the plane of rotation of the arms 12 and so as to impinge against a plurality of pockets 19, provided on the interior of the casing 3, the shorter walls of which pockets are substantial 100 radially to said casing and are connected by long inclined or curved walls, which connect the base of one short wall with the apex of the next, so that the jets projected from the motor-arms 12 will impinge most 11 directly against the short radial walls, thus exerting the highest efficiency in rotating the shaft 4. As a result of this construction the force exerted by the jets projected from the arms 11 and the pressure of steam within the box 2 against the flange 7 will tend to force the shaft 4 toward the bearing 6 and to

compress the packing washer or ring 9 between the flange 7 and the cap 8, thereby sufficiently packing the joint between the interior of the box 2 and the interior of the casing 3.

Steam entering the box 2 through the pipe 1 will have no outlet, except through the opening 10 into the interior of the shaft 2 and thence into the chamber 13. These 10 passages are preferably so proportioned that in its initial flow steam will enter the chamber 13 much more rapidly than it will flow out through the arms 11 and 12, so that a body of steam under pressure will gather 15 within the chamber 13. As the pressure within the chamber 13 increases the velocity of the flow through the arms 11 12 will correspondingly increase until the inflow through the pipe 1 will equal the outflow through the 20 arms 11 12. The jets projected at high velocity through the arms 11 12 will, in a familiar manner, cause the rotation of the shaft 4, and as the parts are so proportioned that the arms 11 12 will just safely clear the 25 walls of the pockets 16 and 19 the impinging and partial huddling of the steam within said pockets will increase the motor efficiency of the steam in causing the rotation of the shaft 4. The fly-wheel 15 will of course act in the 30 usual manner in steadyng the operation of the mechanism and in tending to continue the rotation of the shaft 4.

Keyed to the outer end of the shaft 4 beyond the stuffing-box 5 is a disk 20, to which 35 are pivoted clutch-arms 21. These clutch-arms 21 are held in their normal position, as shown more clearly in Fig. 5, by springs 22, and are provided at their outer ends with weights 23. Stops 24^a serve, in conjunction 40 with the springs 22, to hold said arms in their position of rest. These clutch-arms, it will be noted, are in the shape of a bell-crank lever, the long arm of which in a position of rest extends tangentially to the disk 20.

45 Journaled within the propeller-casing 24 is a shaft 25, supported at one end by a bracket 26 and journaled at the other end in said casing and extending through a stuffing-box 27. Said shaft is also provided with a collar 50 28, which serves as a stop to limit the movement of said shaft in the direction of the motor-casing 3. The free ends of the shaft 2 and the shaft 25 are arranged closely adjacent to each other, and the free end of the 55 shaft 25 has keyed to it a disk 29, which is provided with an annular flange 30, extending toward the disk 20 and around a lateral projection 31 on the short arms of the clutch-levers 21, said projections 31 being provided 60 with a friction-face adapted to make frictional contact with the inner face of said flange 30.

Mounted upon the shaft 25 within the propeller-casing 24 are propeller-blades 32, set at such an angle that in the normal operation

of the device the rotation of the blades 32 will force water out of the casing 24 through the pipe 33. As steam enters through the pipe 1, the box 2, and shaft 4 it is projected through the arms 11 12 into the interior of the motor-casing 3, whence it finds a free outlet through the pipe 34 and is conducted to the water-jacket 35, surrounding the motor-casing 24, which operates as a condenser, the water of condensation being automatically discharged in any suitable manner through the pipe 36. As the rotation of the shaft 4, caused by the projection of steam through the motor-arms 11 12, increases in rapidity the centrifugal weights 23 on the clutch-arms 21 are thrown outwardly against the tension of the springs 22 and the lateral projections are brought into frictional contact with the inner face of the flange 30 on the disk 29. As this frictional contact is established it starts the rotation of the disk 29 until the disks 29 and 20 are rotating in unison, with a corresponding rotation of the shaft 25 and the propeller-blades 32. This rotation of the propeller-blades 32, as before explained, forces water out of the propeller-chamber 24 through the pipe 33 and draws water into the propeller-chamber 24 through the pipe 37. It will thus be seen that with the described embodiment of my invention in its initial 95 operation the motor carries no load, except the friction incident to its own operation, and acquires no load until it has acquired a speed which brings the friction-clutch into operation, such operation of the friction-clutch being to gradually put the load on the motor until the apparatus is running at full speed. It will also be noted that the high speed of rotation acquired by the fly-wheel before the friction-clutch is in operation tends to continue the rotation of the motor as the load is gradually put on it by the operation of the clutch device; but whenever, because of failure of the motive force or for any other reason, the motor slows down the springs 22 will overcome the centrifugal action of the weights 23, the clutch will be disconnected, and the engine unloaded, whereupon it may operate freely and without load until it acquires sufficient velocity to again operate the 115 clutch mechanism connecting it with its load.

I have illustrated an arrangement in which the steam-pipe 34 leads from the motor-casing 3 to a jacket 35, which surrounds the propeller-casing 24, from which jacket the pipe 36 leads to any convenient point. In this arrangement the jacket 35 and casing 24 constitute a convenient form of condenser, which is conveniently arranged immediately adjacent to the motor-casing 3, so as to quickly produce an operative difference in pressure between the inlet-pipe and the exhaust-pipe 34 of the engine, while at the same time utilizing the exhaust of the engine to heat the water of a circulating system. Neverthe- 130

less I contemplate any use to which my engine may be put for carrying any kind of a load and do not limit myself to an apparatus in which the exhaust from the engine is utilized for any purpose whatever. Neither do I limit myself to the use of steam as a motor fluid. So, also, while many variations in details may occur to those skilled in the art as a matter of convenience, shop expediency, or mechanical skill all such changes are within the contemplation of my invention and regardless of whether or not the load is carried directly by the engine or by means of a clutch connection or otherwise.

15 The present application does not relate to my inventions in the condensing and circulating apparatus which are herein shown, but are not herein claimed, such features being shown in my copending application, Serial

20 No. 243,362.

I claim—

1. The combination with a casing, of a hollow shaft mounted therein, a plurality of hollow motor-arms connected with said shaft and communicating with the interior thereof, said motor-arms being arranged to discharge into said casing at different angles but so as simultaneously to rotate said shaft.
2. The combination with a casing, of a hollow shaft mounted therein, a plurality of hollow motor-arms connected with said shaft and communicating with the interior thereof, said motor-arms discharging into the interior of said casing, at different angles but so as to simultaneously rotate said shaft, and two series of pockets arranged within said casing, one series of pockets being adapted and arranged adjacent to the discharge end of a motor-arm discharging at one angle and the other series of pockets being adapted and arranged adjacent to the discharge end of a motor-arm at a different angle.
3. The combination with a casing provided with a main chamber and a motor-fluid-inlet chamber, of a hollow shaft extending into both of said chambers and having longitudinal play in its bearings, said shaft being provided with a passage leading from the interior of said shaft to the interior of the motor-fluid chamber and with an annular shoulder, a suitable seat for said shoulder, and a motor-arm arranged within said main chamber and connected with the interior of said shaft, said motor-arm being arranged to discharge into said chamber so as to rotate said shaft and so also as to draw said annular shoulder against the seat provided therefor.
4. The combination with a hollow rotatable shaft, of a casing provided with a motor-fluid-inlet chamber, said shaft extending through said chamber and said shaft having longitudinal play in its bearings and being provided with a passage leading from the interior of said shaft into said motor-fluid chamber and with an annular shoulder, a

suitable seat for receiving said shoulder, a motor-arm communicating with the interior of said shaft and discharging in such a manner as to rotate said shaft, and means for supplying the motor fluid to said motor-fluid-inlet chamber in such a manner as to rotate said shaft and to also operatively hold said shoulder to the seat provided therefor.

5. The combination with a casing provided with a motor-fluid-inlet chamber having an open space to receive steam, of a hollow rotatable shaft extending into said chamber and provided with a passage leading from the interior of said shaft into said chamber, said shaft being also provided with a non-packing shoulder, a suitable seat for said shoulder, a packing-washer mounted upon said shaft between said shoulder and said seat, all so arranged that the pressure of the motor fluid in said inlet-chamber will cause said shoulder to clamp said washer against said seat, and means communicating with the interior of said shaft for rotating said shaft when motor fluid under pressure is supplied to said inlet-chamber.

6. The combination with a longitudinally-movable shaft provided with a freely-rotating collar, of a casing provided with a fluid-inlet chamber having an open space to receive steam and with a seat for said collar, means for supplying fluid under pressure to said casing, and a fluid-outlet leading from said casing, all so arranged that the fluid-pressure within said casing will force said collar toward said seat.

7. The combination with a casing provided with a fluid-inlet chamber having an open space to receive steam, of a longitudinally-movable shaft extending into said chamber and provided with a shoulder out of contact with the wall of said chamber, of a seat, a packing-ring mounted upon said shaft between said shoulder and said seat, a fluid-outlet passage leading through said chamber, and means for supplying fluid under pressure to said chamber, all so arranged that the fluid-pressure within said chamber will clamp said washer between said shoulder and said seat.

8. In combination, a rotary engine, means for supplying a motor fluid to said engine so as to actuate said engine, means for utilizing the exhaust from said engine in varying quantities, thereby varying the flow of the motor fluid to said engine, a load-shaft, and means for automatically connecting the shaft of the engine with the load-shaft whenever the engine attains a certain speed and for automatically disconnecting said shafts from each other whenever the engine drops below said speed.

EGBERT H. GOLD.

It is hereby certified that in Letters Patent No. 848,985, granted April 2, 1907, upon the application of Egbert H. Gold, of Chicago, Illinois, for an improvement in "Engines," an error appears in the printed specification requiring correction, as follows: In lines 100-101, page 1, the words "substantial radially" should read *substantially radial*; and that the said Letters Patent should be read with this correction therein that the same may conform to the record of the case in the Patent Office.

Signed and sealed this 16th day of April, A. D. 1907.

[SEAL.]

F. I. ALLEN,
Commissioner of Patents.
